UNITED STATES PATENT OFFICE

JOHN W. CARLSON, OF CHICAGO, ILLINOIS, ASSIGNOR TO HEDMAN MANUFACTURING COMPANY, OF CHICAGO, ILLINOIS, A CORPORATION OF ILLINOIS

CHECK WRITER

Application filed September 7, 1929. Serial No. 391,068.

My invention relates generally to check writers and more particularly to improvements in the means for scarifying the payee name line of a check or other negotiable instrument and in clearing the set-up of the machine.

A number of check writers at present on the market are provided with means for scarifying the paper at the place where the payee name is written, thereby to prevent alteration of the check by substituting the name of a different payee. Some of these machines require an additional manual operation to effect this scarification on the payee name line. While in the machine of my invention an additional manual operation is required, this operation is so related to the operation of clearing the set-up of the machine that it requires but little additional effort on the part of the operator and will become habitual. More specifically, I have provided mechanism for operation of the payee name scarifying means upon slight downward movement of the clearing bail which my invention relates.

Another difficulty frequently encountered in check writing machines is that it is impossible conveniently and readily to vary the impression stroke of the apparatus so that some thin checks or papers to be protected are unduly mutilated, while the check or other instrument of heavier paper is insufficiently scarified. I have therefore provided an improved means for varying the pressure by which the type are forced against the platen.

It is therefore one of the primary objects of my invention to provide an improved means for operating the payee name scarifying means of a check writer.

A further object is to provide an improved means of this type which is operated by the set-up clearing bail.

A further object is to provide an improved operating mechanism for a check writer in which are incorporated means to vary the force of impression.

A further object is to provide an improved operating means for check writers in which

the main operating shaft is eccentrically mounted in rotatable members so that rotation of said members will move the shaft laterally.

Other objects will appear from the following description, reference being had to the accompanying drawings, in which

Fig. 1 is a perspective view of the rear of the check writer, the upper and rear portion of the casing being removed to show the working parts;

Fig. 2 is a detailed vertical section showing the full stroke mechanism;

Fig. 3 is a central vertical sectional view of the machine, several of the well-known parts thereof being omitted; and

Fig. 4 is a left side elevation of my improved check writer with portions of the casing broken away to show the operating parts.

The machine of my invention constitutes an improvement on check writers of well-known construction, such, for example, as that shown in the patent to C. M. Hedman, No. 1,703,106, granted February 26, 1929. It comprises a base 10 having suitable rubber feet 12. Serrated platens 14 and 16 are rigidly mounted in the base 10 in any suitable well-known manner, the platen 14 being adapted to cooperate with complementally serrated type to print and scarify the amount characters upon a check, and the platen 16 being adapted to cooperate with a complementally serrated matrix 18 carried by a resilient sheet 20 which is secured to the base 10 by screws 22.

A pair of side frames 24 and 26 is formed from a single sheet of metal, the frames being joined by a horizontal plate portion 28 and secured to the base by screws 30. A shaft 32 is mounted in the side frames 24 and 26 and forms a pivotal axis for the type carrying frame plates 34 and 36 in the usual manner. The type carrying frame is normally held in raised position by a pair of torsion springs 38 which are coiled about the shaft 32 and have their ends bearing against lugs 40 struck inwardly from the frame plates 34 and 36 and the plate 28, respectively.

The type bearings discs or segments 42, which are adapted to be rotatably moved by finger pieces 44 to position any selected type in printing position, are mounted on a central shaft 46, the ends of which are carried in the frame plates 34 and 36. The type are thus adapted to be moved toward and away from the platen 14 upon oscillating movement of the frame plates 34 and 36 about the shaft 32. The frame plates are joined by a heavy cross bar 48 which at its center has a pair of similar brackets 50 supporting a stub shaft 52 upon which a roller 54 is mounted for free rotation.

15 An operating handle 56 is rigidly secured to a shaft 58 which is rotatably mounted in bearings 60 and 62, each of which comprises a plurality of washers which are secured together to form a single bearing by means of screws 64, the screws being threaded in arms 66 of a cross bail 68. The bearing members 60 and 62 are thus rotatable as a unit. It will be noted that the shaft 58 is mounted eccentrically in these bearing members 62.

A short arm 70 formed integrally with a washer shaped plate 72 is secured to the bearing member 60 by the screws 64 and has a cap screw 74 threaded therein, the head 30 of the cap screw lying outside of a sheet metal casing 76 and its shank projecting through an arcuate slot 78 formed in the casing. When this cap screw is loosened the bearing members may be manually rotated 35 through an angle limited by the arcuate slots 78 and may be clamped in adjusted position by tightening the cap screw 74 against the casing.

Centrally mounted upon the shaft 58 and 40 rigidly secured thereto is a cam 80 which is adapted to cooperate with the roller 54 and upon rotation of the shaft thereby force the frame plates 34, 36 downwardly, carrying the type into engagement with the platen 14. By rotating the bearing members 60, 62, the shaft 58, due to the eccentricity of its mounting, will be moved toward and away from the roller 52 and thus the distance which the cam will be able to move the 45 frame plates 34, 36 will be correspondingly varied.

After a check has been printed it is desirable, unless the next check to be protected is of the same denomination, to clear the 55 set-up of the type discs or segments 42. This is done by means of a bail 82 having arms 84 pivoted on the shaft 46. The bail has a plate-like extension 86 which may be manually grasped to swing the bail upwardly, thereby "picking up" the finger pieces 60 and restoring them to their initial positions.

The bail is normally held in the position 65 shown by a pair of springs 88 which are tensioned between studs 90 threaded in the

plates 24 and 26, respectively, and links 92 which are pivotally connected to the rearward extensions 94 of arms 84. These rearward extensions 94 have suitable arcuate slots 96 cut therein to receive studs 98 projecting sidewardly from the ends of links 100, the other ends of the links being pivotally joined to arms 102 which are secured to a shaft 104 rotatably mounted in the plates 24 and 26. Rigidly secured to the shaft 104 75 is a pair of arms 106, the ends of which are joined by a short shaft 108 upon which a roller 110 is freely rotatable.

Pivots hung from the shaft 58 is a pair 80 of arms 112 which at their lower ends are joined by a cross bar 114 substantially S shaped in cross section. The arms 112 have forward projections 116. Links 118 each have one end pivotally connected to the forward end of projections 116, their other ends 85 being pivotally joined to a presser lever 120 which is pivoted about the shaft 32 and has a forwardly and downwardly projecting foot portion 122 which is adapted to engage the upper surface of the matrix 18.

A grasshopper spring 124 has one end lodged in the kerf of screw 22, is coiled about the shaft 32, and has its other end engaging in front of the cross bar 114, and thus serves normally to swing the arms 112 rearwardly, 95 thereby raising the presser levers and permitting the spring plate 20 to raise the matrix from its platen 16.

A full stroke mechanism, shown in Fig. 2 may be provided to prevent reverse rotation of the shaft 58 to force the operator to complete a full revolution of the handle after it has been rotated counter-clockwise beyond a predetermined point. This mechanism comprises a notched plate 126 rigidly 100 secured to the shaft 58 and a stop pawl 128 which is mounted for free pivotal movement upon a stud 130 and the tooth of which is normally held in contact with the edge of the plate by a spring 132. This type of full 105 stroke mechanism is well known in the art and it is believed unnecessary to describe it herein in further detail.

In operation the check to be protected is inserted between the platens 14 and 16 and 115 the matrix 18 in the usual manner and the finger pieces 44 moved to set the desired amount type in printing position. If the paper of the check to be protected is unusually thin, the cap screw 74 is loosened and 120 swung to the uppermost end of the arcuate slot 78, thereby moving the shaft 58 laterally away from the roller 54. The cap screw is then tightened so as to lock the bearing members 60, 62 in this set position. Conversely, if the paper of the check is extremely thick, the cap screw is swung to the lowermost end of the slot 78, thereby laterally 125 moving the shaft 58 toward the roller 54 and consequently, upon operation of the ma- 130

chine, causing the type to be pressed more firmly against the platen 14.

To operate the machine, the operating handle 56 is rotated one full turn counter-clockwise (Figs. 3 and 4) whereupon the cam 80 will engage the roller 54 and through the latter force the frames 34, 36 downwardly, pivoting them about the axis of the shaft 32 and forcing the selected type against the platen to print and scarify the check. It will be understood that the usual means for inking the type, such, for example, as shown in the aforementioned Hedman patent, are provided.

Upon completion of the amount impressing operation the operator will grasp the plate 86 and swing the bail 82 upwardly in the direction of the arrow A, thereby restoring the finger pieces 44, and hence the type segments 42, to normal position. The slot 96 in the rearward extensions 94 of the bail elements 84 will permit this movement without affecting the mechanism for forcing the matrix 18 against its platen. After restoring the type segments 42 the bail 82 is swung downwardly in the direction of the arrow B, thus moving the links 100 rearwardly, swinging the arms 102, and hence the shaft 104, clockwise, and depressing the roller 110 against the cross bar 114. Downward movement of the roller 108 will cause the arms 112 to be swung forwardly and through the links 118 swing the presser levers 120 downwardly until the foot portions 122 thereof engage the matrix 118 and force the latter to scarify the payee name portion of the check which lies between the matrix and its platen 16. Upon release of the plate 86 the spring 124 will restore the last described mechanism to normal position and the springs 88 will return the bail 82 to the position in which it is shown.

The invention is capable of wide variation within equivalent limits and I contemplate such variation as may be desirable or useful in the particular adaptation of the invention shown, or in its adaptation to other machines. I do not restrict myself in any unessential particulars, but what I claim and desire to secure by Letters Patent is:

1. In a check writer, the combination of a base, a serrated platen mounted on said base, a frame pivoted relative to said base, printing type mounted in said frame for selective cooperation with said platen, a pair of plates rigidly secured to said base, a bearing member rotatably mounted in each of said plates, an operating shaft eccentrically mounted for rotatable movement in said bearing members, a cam secured to said operating shaft, a roller mounted on said pivoted frame and engageable with said cam, and means for adjustably rotating said bearing members 65 and holding them in adjusted position

whereby the position of said cam relative to said roller may be adjusted so that upon rotation of said shaft the type in said frame will be moved a predetermined distance relative to said platen.

2. In a machine of the class described, a platen, serrated type movable toward and away from said platen, operating means including a rotatable cam and cam shaft for moving said type to impressing position, and unitary means simultaneously operable at both ends of said shaft for adjusting the position of said cam whereby said type may be moved a predetermined distance toward said platen upon normal operation of said operating means.

3. In a machine of the class described, the combination of a plurality of type carrying members, finger pieces for selectively positioning said members, a platen for said type, a second platen adjacent said first-named platen and adapted to scarify the payee name portion of a check, a matrix cooperable with said second platen, a finger piece restoring member, and means for pressing said matrix against said second platen upon movement of said member.

4. In a check writer, the combination of a pivoted frame carrying selectively settable type members, a platen for said type, a rotatable shaft having a cam for moving said frame toward said platen, a handle for rotating said shaft and cam, and unitary means simultaneously effective upon both ends of said shaft for changing the relationship between said cam and said frame thereby to determine the distance said frame and type members will be moved toward said platen upon operation of said handle.

5. In a check writer, the combination of a pivoted frame carrying selectively settable type members, a platen for said type, a pair of side plates, bearing members rotatably mounted in said side plates, a shaft rotatably mounted in said bearing members eccentric of the axes thereof, an operating handle secured to said shaft, a cam secured to said shaft and adapted to move said frame toward said platen, and means for adjustably positioning said bearing members by rotating them relative to said side plates thereby to vary the distance which said frame will be moved toward said platen upon rotation of said operating handle.

6. In a check writer, the combination of a base, a pair of platens mounted in said base, a pivoted frame carrying selectively settable type members cooperable with one of said platens, a matrix movable toward and away from the other of said platens, and a manually engageable member operable when moved in one direction to re-set said type to normal position and when moved in the other direction to move said matrix toward its platen.

7. In a check writer, the combination of a base, a pair of platens mounted therein, a frame movable relative to said base and carrying selectively settable type members 5 cooperable with one of said platens, a matrix cooperable with the other of said platens, a bail for restoring said type members to normal position, and an operative connection between said bail and said matrix 10 whereby said matrix will be forced toward its associated platen when said bail is moved in a direction opposite to that of its restoring movement.
8. In a check writer, the combination of 15 a base, a platen secured to said base and adapted to scarify the payee name portion of a check, a matrix movably mounted on said base and adapted to cooperate with said platen to scarify said portion of a check, a pair of levers having foot portions engageable with said matrix to press the latter against said platen, a manually operable bail, and a lost motion connection between said bail and said levers whereby said matrix 20 may be forced against its platen upon movement of said bail in one direction and remain inoperative when said bail is moved in the opposite direction.
9. In a check writer, the combination of 25 a base having a pair of platens mounted thereon, a frame movable relative to said base and carrying a plurality of selectively settable type members cooperable with one of said platens, manually engageable means 30 for setting said type members, a type restoring member engageable with said last-named means to restore said type members to normal position, a matrix cooperable with the other of said platens, and an operative connection between said restoring member 35 and said matrix for moving the latter against its associated platen upon movement of said restoring member.
10. In a check writer, the combination of 40 a base having a frame rigidly secured thereto and a frame pivotally secured thereto, a platen carried in said base, a plurality of manually settable type carrying elements mounted in said movable frame, a pair of bearing members adjustably mounted for rotation in said rigid frame and having bearing apertures eccentric of the axes thereof, an operating shaft journaled in said bearing members, and a cam secured to 45 said shaft and operable upon rotation thereof to force said movable frame downwardly thereby to cause printing engagement of the type on said type carrying elements with said platen.
11. In a check writer, the combination of 50 a stationary frame having a platen associated therewith, a frame movable with respect to said stationary frame, type carrying elements adjustably positioned in said movable frame, a pair of bearing members 55
- rotatably mounted in said stationary frame, means rigidly connecting said members, means to lock said members in adjusted position, an operating shaft mounted for rotation in said members eccentric of the axes 70 thereof, and cam means carried by said shaft and cooperable with said movable frame thereby to force the type carrying elements into engagement with said platen upon rotation of said operating shaft. 75
12. In a check writer, the combination of a stationary member having a platen associated therewith, a frame pivotally connected to said stationary member, a plurality of type carrying segments pivotally 80 mounted in said pivoted frame and arranged for manual adjustment to present selected type thereon in alignment with said platen, a pair of bearing members rotatably mounted in said stationary frame, simultaneously operable means to rotate both of said bearing members and lock them in any selected position, an operating shaft rotatably mounted in said bearing members eccentric of the axes thereof, a roller carried 85 by said pivoted frame, a cam secured to said operating shaft and cooperable with said roller thereby to depress said pivoted frame and force the selected type thereof into engagement with said platen, and resilient means to return said pivoted frame to normal position. 90
13. In a check writer, the combination of a pair of platens, selectively settable type members cooperable with one of said 100 platens, a matrix cooperable with the other of said platens, and common manually operable means for restoring said type members to normal position and causing said matrix to be engaged with its associated platen. 105
14. In a check writer, the combination of a pair of platens, selectively settable type members engageable with one of said 110 platens to imprint and scarify an amount designated thereon, a matrix cooperable with the other of said platens to scarify a portion of the check adjacent that upon which the amount designation is printed and scarified, manually engageable means for 115 restoring said type members to normal position, and an operative connection between said means and said matrix for causing said matrix to engage its associated platen upon operation of said means. 120
- In witness whereof, I hereunto subscribe my name this 4th day of September, 1929.
- JOHN W. CARLSON.
